The ornamental design for an air delivery tube, as shown and described.

DESCRIPTION

FIG. 1 is a perspective view, from the front, top, right side, of an air delivery tube showing a first embodiment according to our new design;

FIG. 2 is a perspective view from the front, bottom, right side, thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is another perspective view; and,

FIG. 10 is still another perspective view.

The broken lines in the drawings illustrate portions of the air delivery tube that form no part of the claimed design.
